DESIGN FOR A KITCHEN NOVELTY MAID

Florence E. Rocus, Santa Barbara, Calif.

Application May 5, 1933, Serial No. 48,020

Term of patent 7 years

To all whom it may concern:—

Be it known that I, FLORENCE E. Rocus, a citizen of the United States of America, residing at 736 E. Yanonali Street, Santa Barbara, in the county of Santa Barbara, State of California, have invented a new, original, and ornamental Design for a Kitchen Novelty Maid, of which the following is a specification, reference being had to the accompanying drawing, forming part thereof in which:

Fig. 1 is a front view of the kitchen novelty maid showing my new design;

Fig. 2 is a side elevational view of the kitchen novelty maid shown in Fig. 1; and

Fig. 3 is a back view of the kitchen novelty maid shown in Fig. 1.

I claim:—

The ornamental design for a kitchen novelty maid, as shown.

FLORENCE E. ROCUS.
